UNITED STATES PATENT OFFICE

EDWARD BENTON WAGNER, OF MILTON, INDIANA

TABLE

Application filed July 19, 1930. Serial No. 469,242.

This invention relates to a table, the general object of the invention being to provide means whereby the legs of the table can be easily moved to folded and unfolded position and firmly held in unfolded position.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of one-half of the improved table.

Figure 2 is a similar view but showing a modification.

Figure 3 is a bottom plan view of Figure 1, with the legs folded.

Figure 4 is a bottom plan view of Figure 2, with the legs folded.

Figure 5 is a section on line 5—5 of Figure 3.

Figure 6 is a section on line 6—6 of Figure 4.

Figure 7 is an enlarged sectional detail view showing the wedge means between a leg member and a brace member and the hinge construction of the first form of the invention.

Figures 8, 9, 10 and 11 are views of a further modification, Figure 10 being a section on line 10—10 of Figure 9.

Referring to Figures 1, 3, 5 and 7, the table top is shown at 1 and one pair of legs at 2. These legs are connected together by the cross bar 3. A brace bar 4 is hinged at its inner end to a central cross piece 5 fastened to the bottom of the table, the hinge being shown at 6. A hinged leaf 7 is connected to the under side of the bar 4 adjacent its other end and a leaf 8 is connected to the inner side of the cross piece 3. A center leaf 9 is pivotally connected with the leaves 7 and 8 so that the bar 4 can be swung upwardly and will draw the legs 2 with it, as shown in Figures 3 and 5. A plate 10

of spring metal is fastened to the upper edge of the leaf 8 and is flanged as at 11. This flange 11 bears against the lower part of the plate 8 and thus makes the plate 10 in the shape of a wedge which is engaged by the lower end of the bar 4 when the legs are unfolded. The spring nature of this wedge part of the plate 10 will thus cause the parts to frictionally engage each other and thus the parts will be firmly held in a position with the legs open. It will, of course, be understood that the other half of the table is formed in the same manner.

In the modification shown in Figures 2, 4 and 6, the leaf A has but a pair of leaves and the leaf 12 is fastened to a clip 13 of substantially U shape which slides on the brace bar 4'. A plate 14 is fastened at the lower end of the bar 4' and has its inner end bent downwardly to provide a flange 15 which limits the downward movement of the clip. In other respects, this form of the invention is the same as that before described. Thus it will be seen that I have provided simple means for permitting the legs of a table to be folded, the parts automatically dropping to operative position when the table top is lifted and when the table is to be folded, it is simply necessary to exert pressure on the brace bars to cause the legs to fold against the under side of the table top.

In the modification shown in Figures 8 to 11, the brace bars 4" are hinged to the central bar 5', as in the first form of the invention and each brace bar has sliding engagement with the bent end of a U-shaped member 16, the ends of the limbs of which are bent at right angles and pivoted to the legs by the clips 17. A plate 18 is fastened to the lower side of each brace bar adjacent its free end with the inner end of the plate enlarged so that it extends beyond the sides of the bar. Thus when the legs are swung to operative position and the brace bars lowered, the projecting portions of the plate will engage the bent portions at the free ends of the members 16 and thus limit the downward movement of the brace bars and hold the brace bars with their free ends en-

gaging the beveled portions 19 formed on the cross pieces of the legs at the centers thereof, as shown in Figure 1. By pushing upwardly the brace bars, the parts will be folded against the top of the table, as shown in Figures 9 and 10 and in this position, the bights of the members 16 will fit in grooves 20 formed in the under side of the table top. By swinging the legs downwardly from their folded position, the parts will be automatically moved into operative position to hold the legs extended.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A table of the class described comprising a top, a pair of legs hinged to each end thereof, a cross bar connecting the legs of each pair together, a pair of brace bars hinged to an under part of the top at the center thereof, a U-shaped member pivoted to each cross bar and having its looped end bent upwardly to receive each brace bar therein and a plate on each brace bar having portions engaging the bent-up part of the U member when the free end of the brace bar is in engagement with the cross bar.

2. A table of the class described comprising a top, a pair of legs hinged to each end thereof, a cross bar connecting the legs of each pair together, a pair of brace bars hinged to an under part of the top at the center thereof, a U-shaped member pivoted to each cross bar and having its looped end bent upwardly to receive each brace bar therein and a plate on each brace bar having portions engaging the bent-up part of the U member when the free end of the brace bar is in engagement with the cross bar, that part of the cross bar which is engaged by the free end of the brace bar being beveled.

In testimony whereof I affix my signature.
EDWARD BENTON WAGNER.
